Primary Examiner — Kevin K Rudzinski*Assistant Examiner* — Mehri Bajoul(74) *Attorney, Agent, or Firm* — Mark D. Bowen Esq.; Malin Haley DiMaggio & Bowen, P.A.(57) **CLAIM**

The ornamental design for a trailer hitch mounted Bimini ring toss game, as shown and described.

DESCRIPTION

FIG. 1 is a top front perspective view of a trailer hitch mounted Bimini ring toss game in accordance with the present invention;

FIG. 2 is a bottom rear perspective view thereof;

FIG. 3 is a top view thereof;

FIG. 4 is a bottom view thereof;

FIG. 5 is a side view thereof, the opposite side being a mirror image;

FIG. 6 is a side view thereof in relation to a vehicle;

FIG. 7 is a front view thereof;

FIG. 8 is a rear view thereof;

FIG. 9 is a front top exploded perspective view thereof;

FIG. 10 is rear bottom exploded perspective view thereof; and,

FIG. 11 is a side exploded view thereof.

The broken lines in FIGS. 1 and 6 illustrate the environment in which the design is used and form no part of the claimed design.
